UNITED STATES PATENT OFFICE.

ROBERT M. BOYD, OF RACINE, WISCONSIN.

RAILWAY-SPIKE.

SPECIFICATION forming part of Letters Patent No. 328,103, dated October 13, 1885.

Application filed January 17, 1885. Serial No. 153,214. (Model.)

To all whom it may concern:

Be it known that I, ROBERT M. BOYD, of the city of Racine, county of Racine, and State of Wisconsin, have invented certain new and useful Improvements in Railway-Spikes; and I do hereby declare that the following is a full, clear, and exact description of the invention, which will enable others skilled in the art to which it appertains to make and use the same, reference being had to the accompanying drawings, which form part of this specification.

Figure 1 is a front view of my improved spike; Fig. 2, a side view; Fig. 3, a perspective; and Fig. 4, a series of sections on the lines indicated in Fig. 1, showing the form and proportions of the spike at different points.

Corresponding parts in the several figures are denoted by like letters of reference.

Owing to the scarcity and high price of oak and other hard-wood ties railway companies have been obliged to adopt the softer woods, and have long felt the necessity of a track-spike suitable for use with such soft ties. Certain qualities are essential to such a spike. For instance, it must be able to resist the outward side pressure of the rail; hold tenaciously when driven into soft wood; be capable of being used where the common spike is now used—for instance, in the ordinary nine-sixteenths slots cut in rail-flanges or in angle-bars; adapted to be driven and withdrawn by the ordinary track tools, and so formed that it shall drive squarely and hug tightly against the rail-flanges.

My invention relates to improvements in a spike that fills in a pre-eminent degree every one of the above essentials; and said spike is especially adapted to the soft woods. The great width of back prevents it giving away from side pressure of rail-flange, and its great amount of bearing surface with the compressed fiber in the channeled sides will make it hold with the greatest tenacity against any drawing force. Every claim made for this spike in soft wood will apply with equal force to hard wood.

The efforts of those who have endeavored to fill the above requirements by the invention and introduction of the triangular or the T-shaped spike have only increased instead of diminishing the obstacles they sought to over-

come, as spikes so constructed present a sharp-edged flange or rib to the wood, that acts as a wedge to divide the fiber, thus preparing a way for the spike-body to follow. This increases the liability of the spike being forced from its bed by the side pressure of the rail. In fact, they do not offer as great a resistance as the old ordinary square-shanked spike. Furthermore, these triangular or T-shaped spikes are difficult to drive from their tendency to twist and dodge if they come in contact with a knot or other hard substance.

The form and construction of the spike will be readily understood upon referring to the annexed drawings, in which A indicates the head of the spike; B, nicks or depressions in the rear flange immediately below and at each side of the head; C, the neck or solid body of the shank just below the head and of the same width as the front flange; D, the chin, and F and G the front and rear flanges, connected by a web, H, thus forming channels or grooves *aa* in the side faces of the spike.

The lower end of the spike is beveled from the front downward toward the lower end of the rear flange, as shown in Figs. 1, 2, and 3, the result of which is that both flanges F and G are made to present sharp chisel-edges at the lower ends, as shown at I and K. These sharp edges sever the grain of the wood into which the spike is driven, making a clean, sharp cut, and insuring a firm and solid backing for the flanges, whereas the forms hitherto adopted have tended to tear and disrupt the fiber of the wood, and to produce a jagged hole, the walls of which yield more or less under pressure against the spike and rot or decay in a comparatively short time.

The front flange, F, is made of the same width as the common spike, in order that it may enter the seats or slots cut in the rail-flanges and angle-bars now in use, but the rear flange is made considerably wider than the front flange and wider than any spike now in use, to present a broad bearing-face to the wood into which it is driven. This widening of the rear flange is a very important feature of the invention. The channels *aa* in the side faces of the spike also serve important purposes—firstly, in rendering the spike light; secondly, in increasing the amount of surface in contact with the wood and propor-

tionately adding to the tenacity of its hold in the wood; and, lastly, by affording spaces into which the wood at each side of the spike enters and is compressed in the form of tenons, which give great additional support to the spike against outward pressure of the rail. Incidentally, too, the channels or grooves lessen the displacement of the fiber of the wood, decrease the tearing or breakage thereof, and facilitate the driving.

The chisel-points and the broad flange G prevent the twisting or turning of the spike in driving, and the beveling of the end downward from the front to or toward the back causes the upper end or head to hug closely against the rail as the spike is driven into the wood.

For the purpose of facilitating the entrance of the spike into the wood and of causing it to become more firmly embedded with each driving stroke, the flanges F G and the web H are made gradually tapering from the upper to the lower end, as shown in Fig. 1, and as indicated by the sections shown in Fig. 4, and the lower end of each is beveled somewhat more sharply to produce a wedge-like point, as best shown in Figs. 1 and 3, thus causing a greater compression of the wood in contact with the web and edge of the flanges.

If extended entirely to the head of the spike, the channels *a a* might permit the entrance of water at the sides of the spike and cause the wood to rot away. To prevent this the channels are stopped some little distance, usually from a quarter of an inch to one inch, below the head A, leaving a solid neck, C, as shown in Figs. 2 and 3, so that when the spike is driven to place the solid portion C overhangs and covers the channels and the wood extending into them.

By referring to Figs. 2 and 3 it will be seen that the chin D is curved to conform with the flange or base of a rail, thus insuring a more perfect bearing and a firmer hold upon the rail than where the chin is simply beveled or inclined.

Owing to the greater width of rear flange G, the implement used for extracting common spikes could not be used with this if the flange were carried of its full width up to the head A; hence I form the nicks or depressions B in said flange just below the head, and thus afford an entrance for the ordinary claw or extracting tool.

It is not necessary that the bevel or inclina-

tion of the lower end be all in one direction, the only essential requisite being that it be so brought to a point that it shall readily enter the wood and that the flanges be made with chisel ends or points, which may be done by 60 beveling the end from the front and back flanges toward the middle of the web H.

It is important that the channels *a a* be left open and unobstructed at their lower ends, as otherwise the chisel could not be formed upon 65 the flanges and the driving qualities of the spike would be impaired.

I claim herein as my invention—

1. A spike having front and rear flanges connected by a web, said flanges and web being made of decreasing width from their upper to their lower ends, substantially as shown and described.

2. A spike having flat front and rear flanges and longitudinal channels in its side faces open 75 at their lower ends.

3. A spike-body consisting of a web and two flanges of unequal width, substantially as set forth.

4. An H-shaped spike-body with one of the 80 flanges or sides considerably wider than the other, substantially as described, and for the purpose set forth.

5. A spike with back flange chisel-pointed from front to back, for the purpose described 85 and shown, substantially as set forth.

6. An H-shaped spike having its web and front flange narrowed or tapered laterally at their lower ends.

7. A rail-spike having flat front and rear 90 flanges and channeled sides, the channels being open at their lower ends, and a solid unchanneled portion above the channels and below the head of such depth as to enter the timber and cover the wood in the channels 95 when the spike is driven its proper distance into the timber.

8. A spike having a broad rear flange, G, provided with nicks or depressions B in said flange just beneath the head to permit the entrance of an extracting implement.

9. The herein-described spike having head A, nicks B B, flat neck C, curved chin D, front flange, F, rear flange, G, wider than flange F, web H, and cutting-edges I and K, 105 all substantially as shown and described.

ROBERT M. BOYD.
